SKI

William H. Vinton, Brattleboro, Vt.

Application February 7, 1940, Serial No. 317,756

3 Claims. (Cl. 280—11.13)

This invention relates to skis.

Skis or snow skates have long been in vogue and they provide a source of great amusement in Scandinavian and other countries experiencing snow deposits of relatively long duration.

As is well known by persons skilled in this particular amusement, skis are relatively long and narrow runner like members to the intermediate portions of which the shoes of the users are strapped and comparatively great skill is required in the successful use of same.

Furthermore, the particular construction of the skis is an important consideration both from the standpoint of ease of manipulation as well as assured safety and maximum comfort in the use of same.

The original skis as well as succeeding ones for a relatively long period of time were constructed from wood which of course were considered highly satisfactory.

The wooden skis however, presented many disadvantages in that they were unduly heavy, were subject to comparatively easy breakage with attendant injuries to the users thereof, were subject to warping unless carefully put away when not in use, requiring waxing and dressing treatments as well as being chilled before used.

These recognized disadvantages of the wooden skis were to a large measure overcome by the advent of metallic skis which have heretofore been proposed or used.

While the aforesaid disadvantages of the wooden skis are to a large extent overcome in the construction of skis from metal, it is nevertheless, highly important that the skis be properly designed, proportioned and reinforced in order to offer maximum satisfaction in their use.

It is a primary object of this invention to provide a metallic ski which is of relatively light weight, which possesses sufficient elasticity to conform with irregular snow levels and prevent same from being distorted, cracked or broken when in use and which is properly reinforced to maintain the above noted conditions.

A further object of the invention is the provision of a metallic ski which is preferably constructed from aluminum for maximum lightness and which is capable of being cast in a single piece or in separate pieces in such manner as to be readily connected for use or disconnected for storage or transportation.

A still further object of the invention is the provision of a metallic ski which is relatively simple in construction, which is capable of manufacture at relatively low cost and which fulfills

the maximum requirements of devices of this kind.

For a more complete understanding of the nature and objects of the invention, reference will be had to the following detailed description, taken in connection with the accompanying drawings, wherein:

Figure 1 is a top plan view of the complete ski constructed in accordance with a preferred embodiment of the invention.

Figure 2 is a side elevation of the ski represented in Figure 1.

Figure 3 is an enlarged and foreshortened top plan view of the rear half portion of the ski.

Figures 3a, 3b, 3c, 3d, 3e and 3f are respectively transverse sections of Figure 3 taken on the corresponding section lines indicated thereon.

Figure 4 is an enlarged and foreshortened top plan view of the front half of the ski.

Figures 4a, 4b, 4c, 4d, 4e, 4f, 4g and 4h are respectively transverse sections of Figure 4 taken on the corresponding section lines indicated thereon.

Figure 5 is a fragmental perspective view showing rigid and flexible connections between corresponding sections of which the ski may be constructed.

Figure 6 is a modified form of rigid connection and Figures 7, 8 and 9 are modified forms of flexible connections.

As is indicated in Figures 1 and 2, the improved ski S is generally of the configuration of those heretofore used, being slightly upwardly bowed as indicated at 10 and having an upturned forward end as indicated at 11.

As indicated in Figure 1 the ski is somewhat wider at its opposed ends than at its mid portion and the front end is smoothly curved as at 12 to the relatively small rounded nose 13.

The ski S embodies a rear portion 14, a front portion 15, and an intermediate portion 16.

For a detailed description of these different portions of the ski reference will now be made to Figures 3 to 4h from which it will be seen that the ski essentially embodies an elongated plate or base 17 which as to its main body portion is relatively thick at the intermediate or shoe engaging portion 16 and gradually diminishes in thickness therefrom toward both the front and rear ends thereof.

The plate 17 has an uninterrupted bottom surface except for a centrally disposed and longitudinally extending channel 18 which is provided for proper guidance in the snow and the bottom surface is slightly upwardly bowed, the interme-

diate portion 16 being normally disposed above a tangent to the opposed end portions as indicated in Figure 2.

The intermediate portion 16 is in itself substantially rigid and may be provided with suitable straps for attachment to the shoes of users. The opposed end portions however, are somewhat flexible or yieldable and the upwardly curved front end 11 is of maximum flexibility to provide for uneven snow surfaces.

In order to provide this required flexibility and at the same time provide against undue distortion or breakage, the portions 14 and 15 are constructed as follows, reference first being made to the rear portion 14.

As indicated in Figures 3 to 3f the base or plate 17 gradually diminishes in thickness from the intermediate portion 16 to a point adjacent the rear end and from there increases in thickness to the end.

The rear end and opposite side edges of the plate 17 are provided with flanges 19 which merge into the opposed edges of the intermediate portion 16 or are interrupted thereby and these flanges gradually diminish in depth and gradually merge into the nose 13 at the front end of the ski.

A transversely arched reinforcing ridge 20 extends from the portion 16 to the rear end of the portion 14. The ridge 20 gradually diminishes both in width and depth from the portion 16 to a point adjacent the rear end from which it gradually increases in width and depth to the rear end.

The ridge 20 is disposed centrally of the plate 17 above the channel 18 and with its axis in the vertical plane of the axis of channel 18. The ridge 20 at its narrowest point adjacent the rear end is interconnected with the opposed flanges 19 by laterally diverging ribs 21.

In the front end portion 15 as indicated in Figures 4 to 4h the plate 17 likewise gradually diminishes in thickness from the portion 16 to a point adjacent the front end where for a short distance the plate is of uniform thickness as indicated in Figures 4f, 4g and 4h.

The guide channel 18 gradually becomes of less depth and merges into the bottom surface of plate 17 short of the front end as is clearly indicated in Figures 4, 4f, 4g and 4h.

The plate 17 at the front portion 15 is likewise reinforced by a longitudinal transversely arched ridge 22 which is disposed immediately above the channel 18 and which gradually diminishes in width and depth from the portion 16 to a point short of the front end where it merges into the relatively thin plate 17.

The absence of the ridge and the relative thinness of the plate 17 at the front end provides maximum flexibility for conformity with irregular snow surfaces to be traversed with the ski.

The reinforcing ridge 22 adjacent the front end of the ski is interconnected with the opposed flanges 19 by means of laterally diverging reinforcing ribs 23.

While the different reinforcing elements have been termed "flanges," "ridges" and "ribs" such terms are used only to distinguish the different elements all of which are integral elongated raised portions on the base or plate 17 for reinforcing same.

It is to be understood that the plate 17 together with the various reinforcing elements is an integral construction and while elements 20 and 22 have been described as ridges they may

be considered as extensions of the intermediate portion 16 and defining with the flanges 19 longitudinal channels which increase in depth and width toward opposite ends of the ski.

As before stated, the ski is preferably constructed from aluminum which possesses many desirable characteristics, chief of which is its relative lightness and by constructing the end portions 14 and 15 in the manner disclosed a ski is provided which is desirably light in weight and the reinforcing elements 19, 20, 21, 22 and 23 effectively prevent distortion and breakage while at the same time permitting sufficient flexibility in the end portions of the ski. The ski may be constructed of plastic material if desired.

While the improved ski may be constructed as a single unit it may be desirable to form same in readily detachable or collapsible sections and accordingly the ski may be constructed as represented in the broken view in Figure 5.

As here represented, the opposed sections 16a, 16b may have overlapping tongues 25 and 26 respectively which are detachably connected by screws or similar securing elements 27. This provides a rigid detachable connection which may be at a point at the longitudinal center of portion 16 or elsewhere in the length of the ski.

According to Figure 6 the rigid connection may comprise a tongue 28 on section 16a receivable in a recess 29 in the section 16b, the connection being maintained by screws 30 extended through the tongue 28 and section 16b.

The sections of the ski may be connected by flexible connections whereby the sections may be folded upon each other to facilitate storage or transportation thereof and accordingly as indicated in Figure 7, the opposed sections 16a and 16b are provided with interfitting tongues 31 and the sections are pivotally connected at 32, the sections being retained against pivotal movement by means of a rod 33 movably disposed in aligned transverse apertures in the tongues.

According to Figure 8 the opposed sections 16a, 16b may have hinges 34 secured to both sides whereby upon releasing one leaf of either hinge the sections may be edgewise pivoted on the other hinge.

According to Figure 9 the sections 16a, 16b are hingedly connected at 35 and retained against pivotal movement by releasable clamping elements 36.

If desired one or more of the detachable connections may be used throughout the length of the ski.

While I have disclosed certain specific embodiments of the invention, same are to be considered as illustrative only, and not restrictive, the scope of the invention being defined in the subjoined claims.

What I claim and desire to secure by United States Letters patent is:

1. A metallic ski comprising an elongated base plate including an intermediate portion and front and rear portions, the intermediate portion being of uniform and maximum thickness, the front and rear portions continuously diminishing in thickness from said intermediate portion toward the opposite ends of the plate, raised elements integral with the plate for reinforcing the front and rear portions, and a guide channel in the lower face of the plate in substantially the longitudinal centre line thereof, said raised reinforcing elements including marginal flanges, medially disposed longitudinal ridges, and diagonally disposed ribs interconnecting the

flanges and ridges adjacent the ends of the front and rear portions.

2. A metallic ski comprising an elongated base plate including an intermediate portion and front and rear portions, the intermediate portion being of uniform and maximum thickness, the front and rear portions continuously diminishing in thickness from said intermediate portion toward the opposite ends of the plate, reinforcing marginal flanges extending from the intermediate portion to points adjacent the opposite ends of the front and rear portions, reinforcing ridges of gradually diminishing width and depth extending longitudinally of the plate from the intermediate portion to points adjacent the ends of the front and rear portions, diagonally disposed ribs adjacent the ends of

the front and rear portions and interconnecting the flanges and ridges, and a guide channel in the lower face of the plate extending longitudinally thereof below the longitudinal center lines of the ridges and terminating at a point spaced from the end of the front portion.

3. A sectional metallic ski comprising an intermediate portion of uniform and substantial thickness, front and rear portions of irregular thickness, and a detachable connection or joint in the intermediate portion for disassembly or folding of the ski, said connection comprising a vertically disposed hinge secured at each side of the sections with the pivots of the hinges in the line of joint between the sections.

WILLIAM H. VINTON.
